UNITED STATES PATENT OFFICE.

ALVIN D. KEENE, OF PITTSBURGH, PENNSYLVANIA, ASSIGNOR TO WESTINGHOUSE ELECTRIC & MANUFACTURING COMPANY, A CORPORATION OF PENNSYLVANIA.

CONNECTER.

Application filed July 6, 1923. Serial No. 649,781.

My invention relates to electric resistance conductors and particularly to connectors for such conductors.

One object of my invention is to provide a relatively simple and compact device for connecting the ends of resistance conductors.

Another object of my invention is to provide a means for connecting the ends of resistance conductors of relatively large area 10 of cross-section and of non-oxidizable material, that shall comprise a member that changes its crystalline structure and oxidizes upon initial application of heat thereto, causing it to increase in lateral area, thereby 15 tightly wedging the conductors in place.

In practicing my invention, I provide a tubular casing, of non-oxidizable material, located around the ends of the conductors and a member that oxidizes and changes its 20 crystalline structure when initially subjected to relatively high temperature, said member being located within said casing and operatively engaging the ends of the conductors.

25 In one modification of my invention, I provide an oxidizable member in which a rust compound is placed to aid in establishing a relatively low resistance path for the current from one conductor to the other at the first application of current thereto.

This rust compound may provide oxygen to aid in the oxidation of the member.

In another modification of my invention, I provide a longitudinally slotted casing 35 having tapering ends, screw-threads on its outer surface adjacent to said ends, and a compression cap at each end to securely clamp the casing on the sleeve.

40 In another modification of my invention, I provide a non-oxidizable casing surrounding slotted ends of the resistance conductor and place in the slots an oxidizable member that is effective to tightly wedge the conductor in the casing upon the initial application of heat thereto.

In the single sheet of drawings,

Figure 1 is a view, in vertical longitudinal section, of an electric resistance furnace comprising a device embodying my invention,

Fig. 2 is a view, in end elevation, of a device embodying my invention,

Fig. 3 is a view, in longitudinal section therethrough, taken on the line III—III of 55 Fig. 2,

Fig. 4 is a view, in end elevation, of a modified form of device embodying my invention,

Fig. 5 is a view, in longitudinal section therethrough, taken on the line V—V of 60 Fig. 4,

Fig. 6 is a view, in side elevation, of another modification,

Fig. 7 is a view, in lateral section therethrough, taken on the line VII—VII of 65 Fig. 6,

Fig. 8 is a view, in side elevation, of a still further modification,

Fig. 9 is a view, in lateral section therethrough, taken on the line IX—IX of 70 Fig. 8,

Fig. 10 is a view, in side elevation, of a still further modification,

Fig. 11 is a view, in lateral section therethrough, taken on the line XI—XI of 75 Fig. 10, and

Fig. 12 is a view in lateral section of another form of conductor and of a device embodying my invention.

An electric furnace 21 is illustrated 80 schematically in Fig. 1 of the drawings as comprising a plurality of side, top and bottom walls designated by the numeral 22. Each wall may comprise a plurality of bricks or blocks of a suitable heat-insulating refractory material usually employed in the art, or it may comprise relatively large slabs of such material and may also comprise two layers as illustrated in the drawing. The further details of construction of the furnace structure are not illustrated as they form no part of my invention.

A heating element for the furnace comprises a resistor member 23 of relatively heavy wire of nichrome or similar material, 95 that may be preformed to comprise a plurality of end-connected, substantially parallel-extending convolutions. The heating element may comprise a plurality of individual resistor members that are respectively connected by connectors 24 embodying my invention and to be hereinafter described in detail.

The convolutions of the heating element may be supported in any suitable or desired 100 manner within a furnace chamber 25 enclosed by the walls 22. The supporting means illustrated in Fig. 1 of the drawing comprises a plurality of spaced, elongated electric-insulating members 26 that cooperate 110

with the wall to which they are suitably secured to hold the resistor member in its proper operative position within the furnace chamber. The ends of the resistor member 5 may be brought out through suitable bushings 27 in the walls of the furnace structure. As the method of supporting, and the method of bringing out the ends of the resistor member constitute no part of my 10 invention, they are not further illustrated or described in detail.

Figs. 2 and 3 illustrate a particular embodiment of my invention in which an outer tubular casing 28 of a nonoxidizable material 15 such as nichrome has located therein a sleeve 29 of oxidizable material such as steel or iron. Machine screws 31 are provided in the casing 28 in order that the sleeve 29 may be securely held therein when the connector is first assembled in its proper operative position in the ends of the resistance conductors.

The tubular casing 28 and the sleeve 29 are located over the adjacent or abutting ends 25 of two resistor conductors 23. The sleeve 29 has an outer diameter that permits of its fitting closely within the casing 28 and the opening therethrough is of such lateral dimension as to receive the ends of the resistor members 23 with what is usually termed 30 a sliding fit.

The sleeve of a connector of the hereinbefore described construction, when subjected to relatively high temperature, undergoes a change of crystalline structure and it also oxidizes. Both of these changes cause it to swell, increasing its outer diameter and decreasing its inner diameter whereby it exerts a gripping action upon the non-oxidizable 40 conductor ends located therewithin.

A plurality of radial holes 32 may be provided in the sleeve 29 distributed both longitudinally and peripherally thereof, and a filling 33 of a rust compound is placed in these holes before the assembly of the connector. The rust compound may comprise a mixture of iron filings and sal ammoniac or a lead oxide.

When iron filings and sal ammoniac are 50 employed, they quickly change into a red oxide of iron, this change taking place within a relatively short time after the assembly of the connector. As red oxide of iron is a conductor of electricity, it will aid in establishing a path of relatively low electric resistance from one of the conductor ends to the other during the initial operation of the heating element.

The oxidizing action upon the steel or iron 60 sleeve 29 causes the formation of a black oxide of iron which material is a good conductor of electricity. The red oxide of iron produced by the iron filings and sal ammoniac in the openings 32 is changed to a black oxide of iron, accompanied by a liberation 65

of oxygen that further aids in causing oxidation of the sleeve 29.

Figs. 4 and 5 illustrate a modified form of the device embodying my invention. An outer casing 34 of non-oxidizable material 70 is provided with tapering ends 35 and with a screw-threaded outer portion 36 located immediately adjacent to the tapering ends 35. The casing 34 is provided with a plurality of longitudinally extending slots 37 75 at each end of the member 34.

A sleeve 29 of oxidizable material is located within the slotted casing 34 and has a sliding fit therein. Screw cap members 38 operatively engage the screw-threaded 80 portions 36 and permit of tightly clamping the slotted ends of the casing 34 over the ends of the sleeve 29, and also of clamping the outer ends of the sleeve 29 over the ends of the resistor members 23. This construction permits of obtaining good electrical contact between the ends of the resistors 23 and the surrounding sleeve 29 during the initial operation of the heating element of 85 which these members constitute a part.

Figs. 6 and 7 illustrate another modification of the device embodying my invention and comprising a tubular casing 28 that is located over the ends 39 of a flat ribbon conductor that extend in the same direction into 90 the casing 28. A bar 41, of iron or steel, substantially co-extensive with the casing 28 is located between the two ends of the resistance conductors 39, a machine screw 31 being provided to initially tightly clamp the 95 three members within the casing 28.

Upon subjection of the connector to a relatively high temperature, the crystalline structure of the member 41 changes and it also oxidizes, causing a swelling of the member 41 whereby the two conductors 39 are 100 tightly wedged within the casing 28.

Figs. 8 and 9 illustrate another modification of the device embodying my invention in which a non-oxidizable casing 28 extends 110 over the abutting ends of two round resistance conductors 23. The ends are provided with a longitudinally extending opening 42 and a longitudinally extending slot 43. A member 44 of steel or iron, having substantially the same contour in lateral cross-section as the opening 42, here shown as substantially circular in cross-section, is located within the opening 42 and is effective upon being subjected to a relatively high temperature, substantially as hereinbefore described, to swell and tightly wedge the slotted 115 ends of the resistor member 23 within the casing 28.

Figs. 10 and 11 illustrate a still further modification in which the ends of the resistor members 23 are respectively provided with a longitudinally extending slot 43, within 120 which an oxidizing member 44, of bar shape, may be located. Upon application 125

of heat thereto, the member 44 swells, as hereinbefore described and tightly wedges the slotted ends of the resistor member 23 in the casing 28.

5 In Fig. 12, I have illustrated a tubular casing that is substantially square in cross-section to co-operate with resistance conductors 23 of bar shape that may be slotted, as illustrated in Figs. 10 and 11 and a member 44 of oxidizable material placed within the slot substantially as hereinbefore described.

The device embodying my invention thus provides a relatively simple and compact 15 connector that is effective to provide a tight wedging joint between two conductors of a non-oxidizable material. While I have illustrated a device as applying to a relatively heavy resistor member, it is not restricted 20 thereto, as it may be employed to connect non-oxidizable resistance conductors of relatively moderate diameter or of relatively small thickness.

Various modifications may be made in the 25 device embodying my invention without departing from the spirit and scope thereof, and I desire that only such limitations shall be placed thereon as are imposed by the prior art, or are specifically set forth in the 30 appended claims.

I claim as my invention:

1. A connector for an electric conductor comprising a non-oxidizable casing surrounding the end of said conductor, and a member in said casing operatively engaging said conductor, said member swelling permanently by reason of changes in its crystalline structure and oxidation thereof upon the initial application of heat thereto and thereby wedging the conductor tightly in said casing.

2. A connector for the ends of non-oxidizable electric conductors comprising a non-oxidizable casing located over the ends of 45 said conductors, and a sleeve of oxidizable material located within said casing and operatively engaging said conductors and swelling permanently upon oxidization coincident with the heating thereof, whereby said conductors are tightly wedged in said casing.

3. A connector for the ends of electric conductors comprising a tubular casing having longitudinally slotted ends, a sleeve of oxidizable material located within said casing and operatively engaging the ends of 55 said conductors, and means operatively engaging the slotted ends of said casing for clamping them tightly against said sleeve.

4. A connector for electrical conductors 60 comprising a casing, an oxidizable member therein connecting said conductors and means in said oxidizable member for supply-

ing oxygen thereto, said oxidizable member consisting of a material which permanently expands radially, upon being heated, and 65 wedges said conductors in said casing.

5. A connector for electric conductors comprising an outer casing, a sleeve therein connecting said conductors, said sleeves comprising material that oxidizes upon the 70 application of heat thereto, and a means in said sleeve that provides oxygen to aid in the oxidation of said sleeve when heated.

6. A connector for the ends of non-oxidizable electric conductors comprising a non-oxidizable casing located around the ends of 75 said conductors, and a sleeve in said casing operatively engaging said conductor ends and comprising material that changes its crystalline structure and swells permanently 80 upon the initial application of heat thereto whereby the ends of said conductors are tightly wedged in said casing.

7. A connector for the ends of electric conductors comprising a tubular casing of non-oxidizable material surrounding the ends of 85 said conductors, and means located within said casing that swells permanently laterally of said casing upon the initial application of heat thereto, thereby tightly wedging 90 said conductors in said casing.

8. A connector for the ends of electric conductors comprising a tubular casing of non-oxidizable material surrounding the ends of 95 said conductors, and means for automatically permanently wedging said ends in said casing upon the initial application of heat thereto, said means comprising a material that changes its crystalline structure and 100 permanently increases in area of cross-section when subjected to a relatively high temperature.

9. A connector for an electric conductor comprising a non-oxidizable encasing member and an oxidizable member therein that 105 swells permanently upon being heated, for wedging said conductor in said casing.

10. A connector for an electric conductor comprising a non-oxidizable encasing member for receiving the end of said conductor and an oxidizable member in said structure 110 that swells permanently upon being heated for wedging said conductor in said structure.

11. A connector for an electric conductor comprising a non-oxidizable means for receiving one end of said conductor and an oxidizable member therein that swells permanently upon being heated and wedges 115 said conductor in said means.

In testimony whereof, I have hereunto 120 subscribed my name this 2nd day of July, 1923.

ALVIN D. KEENE.
